SPOOL WINDING MACHINE

Charles B. Warren, Westfield, Mass., assignor to
W. Warren Thread Works, Westfield, Mass., a
corporation of Massachusetts

Application January 27, 1933, Serial No. 653,798

6 Claims. (Cl. 242—43)

The object of my invention is to provide a novel machine for winding spools of thread having single tapered ends, said machine comprising, generally, means whereby thread of varying sizes 5 may be wound on a spool having a single tapered end, which spool and its laterally movable mandrel are mounted against longitudinal movement; means being provided for imparting a continuous 10 endwise movement to the traverse mechanism in one direction as the spool is being wound.

My invention comprises, more specifically, a variable speed drive for continuously shifting the traverse mechanism endwise at the desired speed, according to the size of the thread being 15 wound.

My invention further comprises a suitable speed reduction unit for driving the traverse mechanism, manual means being employed for disconnecting the speed reduction unit from the traverse 20 mechanism after the winding of the spool is completed, and means also being provided for automatically returning the traverse mechanism to its normal starting position when released from its speed reduction unit.

My invention still more specifically comprises 25 a movable change speed reduction unit in which the final gear of the unit is normally in mesh with a longitudinally disposed rack carried by the traverse cam, said final gear being manually moved out of mesh with the rack after the winding of the spool has been completed, means being employed for automatically returning the final gear of the speed reduction unit into mesh with its rack when the speed reduction unit is released 30 from its inoperative position and the traverse cam has been returned to its normal starting position.

A practical embodiment of my invention is represented in the accompanying drawings, in which: 40 Fig. 1 represents a partial front view of the winding machine;

Fig. 2 represents a top plan view of the same;

Fig. 3 represents a partial side view of the machine, the speed reduction gear being shown in 45 section in its operative position; and

Fig. 4 represents a detail view showing the speed reduction gear in its inoperative position.

The winding machine herein illustrated generally comprises a rotary traverse cam 1 slidably 50 interlocked with the rotary cam shaft 2 for endwise movement thereon. This traverse cam 1 reciprocates the traverse guide 3, said guide being carried by a guide bar 4 having a stud or roller 5 which travels in the cam groove 6 of the 55 traverse cam 1, said guide bar 4 having a recipro-

cating movement parallel to the spool mandrel 7, on which mandrel is removably mounted the spool 8 having a single tapered end 9.

The spool mandrel has a rotary movement and also a lateral movement but is mounted against endwise movement, the means for accomplishing the rotary movement and the lateral movement of the mandrel being of the usual form and a general description thereof will only be included herein.

The spool mandrel 7 is journaled in a bracket 10 fast on a slide bar 11. The pulley 12 on the main drive shaft 13 is driven from any suitable source of power, not shown herein. A loose pulley 14 is mounted on the shaft 13 adjacent the drive pulley 12. A wide faced spur gear 15 is fast on the drive shaft 13 and it meshes with a spur gear 16 rotatably mounted on the slide bar 11. This spur gear 16 has a bevel gear 17 which meshes with a bevel gear 18 carried by the mandrel 7. The cam shaft 2 is driven from the shaft 13 through the pulley 19, belt 19* and pulley 20, which pulley 20 is fast on a cross shaft 21 which carries a bevel pinion 22 meshing with the bevel gear 23 fast on the cam shaft 2.

The mandrel 7 is yieldingly held at the limit of its inward movement as, for instance, by the usual weight 24, flexibly connected with the arm 25 of the tension device, which tension device is connected through the link 25* with the lever 26 which actuates the slide bar 11.

The rotary traverse cam 1 is yieldingly held at the limits of its endwise movement on the cam shaft 2, by means of a coil spring 27 interposed between the hub 28 of the traverse cam 1 and the hub 29 of the bevel gear 23.

The means which I have shown for imparting a continuous endwise movement to the cam shaft 1 in a direction against the tension of the spring 27 while the spool is being wound, is constructed, arranged and operated as follows:

A longitudinally disposed rack 30 is carried by a sleeve 31 which surrounds the rotary cam shaft 2 and is slidably interlocked with the machine frame 32. The inner end of this sleeve 31 is connected to the hub 28 of the traverse cam 1 to move the cam endwise. In the present instance this sleeve 31 is provided with a head 33 seated within the hub 28, a plate 34 overlapping the head, which plate is secured to the end of the hub.

The change speed reduction unit has its casing 35 pivoted at 36 to the machine frame 32, to swing vertically into and out of its operative po-

sition. The final gear 37 of this speed reduction unit projects through the casing 35 into mesh with the rack 39. A spring 38 extends between the machine frame and a lug 39 projects from the 5 casing 35 and serves to hold the unit in its operative position, a stop 40 on the machine frame limiting the downward movement of the unit. A handle 41 projects from the casing 35 in position to be used for rocking the unit upward 10 to disconnect the final gear 37 from its rack 39 when the winding of the spool has been completed.

The worm drive shaft 42 of the speed reduction unit may be adjusted laterally to bring its 15 worm 43 into engagement with any one of a plurality of concentric rings of teeth 44, 45 or 46 on the under face of the rotary disc 47.

This worm shaft 42 is rotatably mounted in a casing member 48 which may be secured to the 20 casing 35 in the several adjustments above referred to.

The worm shaft 42 may be driven at different speeds from the cam shaft 2 by providing the cam shaft with a stepped-down pulley 49 and 25 the worm shaft 42 with a stepped-up pulley 50, the two pulleys being connected by a belt 51.

In operation: As the winding of the spool starts, the very slow endwise movement of the rotary traverse cam also starts in a direction 30 away from the free end of the spool and this slow endwise movement of the traverse cam continues until the spool is completely wound. This endwise movement of the rotary traverse cam compresses the spring 27. The handle 41 35 of the change speed reduction unit is then grasped and the unit is rocked to move its final gear 37 out of mesh with the rack 39. As soon as the gear 37 is disconnected from the gear 38 the spring 27 will automatically return the rotary traverse cam to its normal starting position. It will be understood that as the spool is wound the mandrel is automatically moved laterally, as is usual in this type of machine.

The variable speed drive for the speed reduction unit and the changeable speed for the reduction unit serve together to adjust endwise movement of the rotary traverse cam to the size of material being wound, between wide limits.

50 It is evident that various changes may be resorted to in the construction, form and arrangement of the several parts without departing from the spirit and scope of my invention, and hence I do not intend to be limited to the particular embodiment herein shown and described.

What I claim is:

1. In a machine for winding spools having single tapered ends, a rotary spool mandrel mounted against endwise movement, a thread 60 traverse guide, a rotary cam for reciprocating it, means for imparting a continuous endwise movement in one direction only, to the cam as the spool is being wound, said means including a speed reduction unit, manually operated means 65 for disconnecting the speed reduction unit from the cam, and means for automatically returning

the cam to its normal starting position when released from the speed reduction unit.

2. In a machine for winding spools having single tapered ends, a rotary spool mandrel mounted against endwise movement, a thread 5 traverse guide, a rotary cam for reciprocating it, means for imparting a continuous slow endwise movement in one direction only, to the cam throughout the entire winding of the spool, said means including a change speed reduction unit, manually operated means for disconnecting the speed reduction unit from the cam, and means for automatically returning the cam to its normal starting position when released from the speed reduction unit.

3. In a machine for winding spools having single tapered ends, a rotary spool mandrel, a thread traverse guide, a rotary traverse cam for reciprocating it, said cam having a longitudinally disposed rack, means for imparting a continuous 20 endwise movement in one direction only, to the cam as the spool is being wound, said means including a movable speed reduction gearing unit having its final gear in mesh with said rack, and means for moving the unit to bring the said 25 final gear out of mesh with the rack.

4. In a machine for winding spools having single tapered ends, a rotary spool mandrel, a thread traverse guide, a rotary traverse cam for reciprocating it, said cam having a longitudinally 30 disposed rack, means for imparting a continuous endwise movement in one direction only, to the cam as the spool is being wound, said means including a movable speed reduction gearing unit having its final gear in mesh with said rack, means for moving the unit to bring the said final gear out of mesh with the rack, and means for automatically returning the traverse cam to its starting position when the said final gear is released from the traverse cam rack.

5. In a machine for winding spools having single tapered ends, a rotary spool mandrel, a thread traverse guide, a rotary traverse cam for reciprocating it, said cam having a longitudinally 45 disposed rack, means for imparting a continuous endwise movement in one direction only, to the cam as the spool is being wound, said means including a pivoted speed reduction gearing unit having its final gear in mesh with said rack, and means for swinging the unit to bring the 50 said final gear out of mesh with the rack.

6. In a machine for winding spools having single tapered ends, a rotary spool mandrel, a thread traverse guide, a rotary traverse cam for reciprocating it, said cam having a longitudinally 55 disposed rack, means for imparting a continuous endwise movement in one direction only, to the cam as the spool is being wound, said means including a pivoted speed reduction gearing unit having its final gear in mesh with said rack, 60 means for swinging the unit to bring the said final gear out of mesh with the rack, and means for automatically returning the traverse cam to its starting position when the said final gear is released from the traverse cam rack.

CHARLES B. WARREN.
